CLAIM

The ornamental design for a cut potato product, as shown and described.

DESCRIPTION

FIG. 1 is a front, top and right side perspective view of a cut potato product;

FIG. 2 is a bottom, rear and right side perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The evenly-spaced broken lines in FIGS. 1–8 illustrate portions of the cut potato product that form no part of the claimed design. The dash-dot-dash broken lines in FIGS. 1–8 illustrate the boundary of the claimed design which forms no part thereof.

1 Claim, 8 Drawing Sheets
